2,182,391

PULP REFINER

Max Skolnik, Chicago, Ill., assignor to National Fibre Corporation, New York, N. Y., a corporation of New York

Application February 11, 1935, Serial No. 6,019

11 Claims. (Cl. 92—26)

This invention relates to the manufacture of pulp from fibrous organic material such as straw and the like, and particularly to processes and apparatus for treating such materials to produce 5 pulp and certain by-products having commercial value.

My improved processes and apparatus are related to those disclosed in my Patents Nos. 1,865,649; 1,924,660; and 1,924,815; however, my present invention is directed particularly to unification and simplification of all the devices required to perform the several process steps, and to the improvement of parts of the apparatus and of the entire process, whereby in one apparatus comprising several interrelated and coordinated mechanisms raw materials are, in a continuous and progressive sequence, converted into commercial pulp and certain by-products.

Other objects of the present invention are to 20 provide an improved apparatus for producing finished commercial pulp from straw or the like in but a fraction of the time required by ordinary apparatus; to provide improved process steps in pulp manufacture whereby longer and stronger 25 pulp fibres are produced; to provide improved process steps in which chemicals and other constituents of the straw material are recovered for commercial use; to provide improved process steps in which the straw material treating liquors are 30 self-fortified by chemicals extracted from the material being treated; to provide improved means for handling the material in bulk quantities during the chemical treatment thereof whereby the material is uniformly treated throughout its 35 entire mass; to provide improved washing means for positively removing the undesired constituents of the material after the same has been loosened by the chemical treatment; to provide such means that handle large quantities of material more 40 rapidly than has been heretofore possible; to provide improved refining means; to provide refining apparatus that in one device performs the functions of several of the devices ordinarily used to obtain the same results; to provide such apparatus 45 arranged in a relatively small simplified unit having several times the capacity of ordinary equipment; to provide such apparatus wherein the refining operation is performed continuously and in a single passage of the material through the 50 mechanism.

Further objects are to provide an improved circuit and conditioning cycle for treatment liquors entrained with the treated materials whereby proper chemical conditions are maintained; and to provide an improved device for effecting the

recovery of chemicals and the refining of valuable lignin by-products.

A specific embodiment of my invention is shown in the accompanying drawings, in which:

Figures 1A and 1B show in a side elevation a 5 complete plant or system for the manufacture of pulp from straw and the like, and for recovering certain valuable by-products, Fig. 1A showing one-half of the apparatus and Fig. 1B showing the other half, the apparatus being divided transversely at approximately its middle.

Fig. 2 is a sectional elevation through the basket loading chamber as taken on line 2—2 of Fig. 1A.

Fig. 3 is an enlarged partially sectioned elevation showing in detail the main spraying compartment and the entering end of the cooking tank.

Fig. 4 is a partially sectioned side elevation of a 15 3-stage pulp washer.

Fig. 5 is a sectional view of the same taken on 20 line 5—5 of Fig. 4.

Fig. 6 is a sectional elevation showing the 25 refiner.

Fig. 7 is an elevation of the entering side of the 30 first wheel of the refiner.

Fig. 8 is a similar view showing the entering side of the second wheel of the refiner.

Fig. 9 is a similar view showing the entering side of the third to eighth wheels inclusive of the 35 refiner.

Fig. 10 is a view showing in elevation the 9th to 12th wheels inclusive of the refiner.

Fig. 11 is a view showing the 13th or last wheel of the refiner.

Fig. 12 is a view showing in elevation the dializer or soda and lignin separating apparatus.

Fig. 13 is a plan view showing one of the plates of the dializer as it would appear in a sectional view taken on line 13—13 of Fig. 12.

Fig. 14 is a similar view of an alternate plate of 40 the dializer.

Fig. 15 is a sectional view taken transversely through a plurality of the plates shown in Figs. 13 and 14, as would appear in a section taken on line 45 15—15 of Fig. 13.

Fig. 16 is a similar view as would appear in a section taken on line 16—16 of Fig. 14.

In the ordinary processes of reducing raw materials to a finished and refined pulp, by removing the encrusting and intercellular materials, such as 50 the resinous, siliceous, glutinous and other matters, harsh and prolonged treatment methods are employed with the result that, if a pure cellulose fibre is obtained, the fibres constituting the refined pulp are greatly weakened and reduced to

undesirably short lengths. Also the apparatus employed is cumbersome and expensive and many separate handlings of the material in treatment are required. Ordinarily the raw material is 5 cooked, or treated, at high temperatures in boilers containing a caustic soda solution and for a period of several hours, then the material is washed to remove the caustic soda and the loosened undesirable materials and passed through a series of 10 refiners or beaters which break up and separate the plant fibres. The beating or refining process is also one ordinarily requiring considerable time for its completion.

The washings or solution containing the 15 encrusting and intercellular materials, or lignins, and entrained caustic soda, are usually treated in various apparatus to recover the soda. However such apparatus is large and expensive and the process is ordinarily one of evaporation and combustion in which the lignins are destroyed or 20 consumed, no attempt being made to save them.

By the present invention the treatment of the raw material is reduced to one continuous process, from the loading of the raw material into the 25 apparatus to the production of finished and completely refined pulp delivered in sheets at the delivery or leaving end of the apparatus; the time required for the refined pulp production is reduced to a fraction of the time ordinarily required; and the recovery of the soda is accomplished continuously in a relatively simple separating apparatus which also preserves the lignins for 30 the production of valuable commercial by-products.

35 As shown in the drawings the invention is embodied in an apparatus which is in itself a practically complete plant for the production of refined pulp from raw material and the recovery of soda and lignins. The apparatus comprises mechanisms for accomplishing each step in the processes, so interrelated that there is one continuous flow of material from the raw material entering end to the refined pulp delivery end and a continuous process of by-product recovery.

45 Raw material such as straw or the like is loaded into fenestrate or perforated baskets or containers, by pneumatic means, in a loading housing 1 from which the loaded basket passes to an enclosed spraying and preheating tunnel 50 2 where the material is thoroughly sprayed and soaked with the caustic soda treating solution.

From the spraying tunnel the baskets of material are automatically passed into a long enclosed tunnel-like cooking tank 3, which is filled 55 with a caustic soda solution automatically maintained at a concentration of approximately 2% and at a temperature of about 200° to 212° F.

During the cooking process the encrusting and intercellular constituents of the raw material are 60 loosened.

The baskets are automatically moved through the cooking tank and require about fifty-five minutes to pass from the entering to the leaving end where they are removed from the tank and carried to a dump 4 in which their contents are emptied upon a conveying means which carries the material to a washer 5.

As the straw passes through the washer the 70 loosened lignins, or encrusting and intercellular substances are removed and the straw after passing through a hydrator, or device for diluting the straw with fresh water, is pumped into a refiner 6 where the plant fibres are beaten and separated. From the refiner the straw, which is 75 now a refined pulp is passed to a device com-

prising a plurality of cylinders 7 which pick up the pulp and transfer it to a felt blanket on which a sheet of pulp is built up, squeezed of its excess free moisture, and passed to a cutting and stacking or folding mechanism. The product being sheets of treated and refined pulp ready for any desired use.

As shown in Fig. 1A the washer 5 is connected with a tank 8 in which the squeezings, or washed out lignins, are collected. This tank is a clarifier 10 in which the heavier or solid materials may settle out of the liquid leaving most of the lignins in solution and suspension. This liquid will be herein termed the dark liquor.

The dark liquor, or liquid, is taken from the 15 tank 8 at the upper part thereof by means of a pump which delivers the liquor to a soda recovery device 9, herein termed the dializer, in which the soda is extracted from the dark liquor and from 20 which the dark liquor, now comprising mostly lignins, is passed into lignin storage tanks for use in the manufacture of certain by-products.

The extracted soda, which is carried in a liquid vehicle as will be hereafter explained, is transferred from the dializer 9 to a storage tank from 25 which it is later removed and passed through a caustic recharging equipment and tank 10 to a second storage tank 11. From the tank 11 the recharged liquid is passed through a series of 30 settling towers 12, in which a precipitate of calcium carbonate is removed, and then by way of a conduit 13 to caustic solution storage tanks 14 which supply the make-up treatment solution 35 for the cooking tank 3.

In order to facilitate a complete understanding of my invention the apparatus will be described in detail in the same order or sequence as the steps involved in the handling of the material being treated. The first step is the introduction of the raw material into the apparatus which is done in the loading chamber 1.

The loading chamber 1 comprises an open ended tunnel-like housing which surrounds a convenient section of a suspended track 15 extending between the dump 4 and the soaking and preheating housing 2. The passage through the loading chamber is arranged to receive baskets or carriers 16 which are carried by the track 15 and have top openings; and at approximately 45 the center of the chamber a raised portion 17 is provided in which are located the discharge nozzles 18 of a pneumatic conveying device 19 arranged to handle the straw or other like raw material for loading the baskets 16. The tracks 50 15 comprise a pair of spaced parallel rails and the baskets 16 are suspended between them on flanged wheels 20 mounted on trunnions extending from the basket ends, as shown in Fig. 2. The baskets or carriers are rectangular fenestrate devices constructed of perforated plates or heavy wire mesh and are provided with a movable cover 21, shown in dotted outline in Fig. 2, which serves as a closure for the top opening. The bottom of each basket is also provided with 55 upwardly extending transverse channels 22 which are spaced across the width of the basket and which extend into the basket for approximately one-third its height. These channels are walled so that the bottom of the basket is closed and 60 serve to divide the contents into several portions so that the treatment solution or liquor can more readily penetrate into the interior and center of the basket load.

As shown the nozzles 18 are disposed so that, 75

when a basket 16 is placed beneath them with its cover 21 opened, they will uniformly distribute the raw material into the basket.

The purpose of the loading chamber is to prevent any loose straw or dust from escaping; and to further assure that dust and straw particles will be confined, a spray 23 is provided to dampen or soak the material as it is being loaded. Also other sprays 24 are located directly beneath the position of the channels 22 and directed upwardly to further soak the raw material in the basket and assure that all of the material load is wet. The sprays 23 and 24 are connected by suitable piping 25 to a pump 26 which handles hot caustic solution drawn from the cooking tank 3. As shown in Figs. 1A and 2 the loading chamber is constructed with an inwardly sloping bottom which connects with a drain 27 by means of which excess liquid and loose straw are removed to be suitably disposed of.

It is because of the preliminary spraying during the loading of the material into the baskets that large bulk quantities of raw material can be readily handled and completely treated in the cooking tank 3, since the preliminary spraying prevents the entrapment of air in the voids within the mass of raw material and the formation of air pockets which would prevent the treatment liquor from reaching the inner portions of the mass when the baskets are immersed in and passing through the tank 3.

After the baskets 16 have been completely filled in the loading chamber they are passed along the track 15, which is inclined toward the spraying and preheating chamber 2, and into this chamber where they are again sprayed with hot treatment liquor, from both the top and the bottom, and where the mass of the material is brought up to a temperature approaching that of the liquid in the cooking tank 3.

By this second spraying operation the raw straw is thoroughly soaked and because of the preheating, the cooking treatment liquors have full effect upon the entire mass the moment the baskets enter the tank 3.

As shown in Figs. 1B and 3, the spraying and preheating chamber is a tunnel-like construction disposed above the cooking tank 3. The entering end is open and the inner or leaving end 50 communicates directly with the cooking tank through the top thereof. The floor of the spraying and preheating chamber 2 extends from its entrance to approximately its middle and the remainder of its length opens into the tank 3. A 55 plurality of sprays 28 and 29 arranged to discharge water against the top and bottom of the baskets 16 respectively are disposed in the open-bottomed portion of the chamber 2. These sprays are supplied with hot caustic solution by the conduit 30, which leads from the pump 26 and since the baskets 15 require approximately ten or twelve minutes to pass through the chamber 2, the material held by the baskets is thoroughly saturated with treatment solution and thoroughly 60 preheated.

As the baskets reach the inner end of the spraying and preheating chamber 2, they are delivered onto an elevator 31 which automatically lowers them into the cooking tank 3. As 65 shown in Fig. 3 an end bumper 32 is provided to keep the baskets 16 from overrunning the elevator 31 after they are delivered onto the same. Also a hydraulic braking arrangement, not shown, is provided to hold the next successive basket on the track 15 until the elevator 31 has returned

empty to its raised position when the brake automatically releases that basket allowing it to pass onto the elevator, and automatically engages the next successive basket to hold the same.

As shown in Fig. 3 that portion of the open bottom of the chamber 2 exactly beneath the sprays 29 is provided with a screen 33 which serves to catch any loose pieces of straw, and yet allow any of the sprayed solution not absorbed by the straw in the gaskets to pass directly downward into the cooking tank 3.

As the elevator 31 delivers a basket 16 into the cooking tank 3, the basket is engaged by an automatic ram 34 which pushes the basket off from the elevator 31 and onto a track 35 which extends substantially the length of the cooking tank 3.

The cooking tank 3 is a long, enclosed tunnel-like structure so constructed that it will contain and support a sufficient quantity of caustic soda treatment solution to completely cover the baskets 16 as they pass through the tank. The caustic soda solution within the tank 3 is maintained at a temperature of from 200 to 212° F., by means of steam coils 36 which are disposed along the bottom of the tank and extend for substantially its entire length, and it is within this tank that the raw material is given its main treatment for loosening the lignins or encrusting intercellular and glutinous materials, which it is 20 desired to remove from the straw, in order to produce a pulp that is substantially pure cellulose.

As will be apparent from Fig. 3 the baskets will 35 pass along the track 15 and through the preheating chamber 2 by gravity. However, after they have been loaded into the cooking tank 3 they must be pushed along the track 35, which is substantially horizontal. Such movement or shifting of the baskets along the track 35 is accomplished by the plunger or ram 34 which pushes the baskets off of the elevator 31, each basket pushing ahead of it the next preceding basket, thus moving an entire train of baskets through the tank 3.

As the baskets reach the leaving end of the tank 3 they are pushed onto an elevator 37 which raises them out of the tank 3 and delivers them, through the action of a ram 38, onto the upper end of the track 15 on which they pass to the 50 dump 4. The elevator 37 is indicated diagrammatically and in dotted outline in Fig. 1A and is of the same construction as the elevator 31 at the entering end of the cooking tank 3. The detailed construction of these elevators being substantially immaterial to this invention, no attempt will be made to further describe them, it being sufficient that they are suitable for the herein indicated purpose.

The elevators 31 and 37 are automatically controlled by means not shown or indicated, and likewise the rams 34 and 38 are automatically controlled. The elevators 31 and 37 are raised and lowered in unison and as a basket 16 is delivered into the elevator 31 and lowered into 65 the tank 3 the elevator 37 which at that instant will be empty, is likewise lowered into the leaving end of the tank 3. When the elevator 31 reaches its bottom position where it is aligned with the track 35, the ram 38 automatically acts to push 70 the basket 16 off the elevator and onto the track 35, pushing the preceding baskets ahead of it. Thus when the tank 3 is filled with baskets, each time a new basket is delivered into the same, a basket at the leaving end will be pushed onto 75

the lowered elevator 37. Then both elevators 31 and 37 are automatically raised to their upper position and the ram 38 automatically acts to push the raised basket off the elevator 37 and onto the track 15. At the same time the brake in the preheating tank 2 simultaneously releases another basket so that it will pass onto the raised elevator 31 for delivery into the cooking tank 3. Thus it will be seen that the entire cycle of basket handling is completely automatic.

As the baskets are pushed off of the elevator 37 by the ram 38, they pass along the downwardly inclined track 15 to the dump 4 where they are automatically inverted by apparatus not herein shown in detail, and their contents empties onto a lateral conveyor merely indicated at 39 in Fig. 1A. The conveyor 39 moves the mass of treated material emptied thereonto laterally relative to the cooking tank 3 and empties such material onto a hopper 40 where the material falls onto an automatic drag arrangement 41 which permits the mass of material to be uniformly delivered to a drag conveyor 42 which delivers the material to the washer 5. The drag arrangement 41, while not shown in detail, is constructed so that it will engage the material falling into the hopper 40 and prevent it from choking the drag conveyor 42.

30 After the material is carried out of the hopper by drag conveyor 42 it is removed therefrom by a plurality of rotating kickers 43 which serve the further purpose of breaking up any chunks or small masses of the material.

35 It is to be noted at this point that while such an arrangement is not shown, a drain pan may be provided beneath the lateral conveyor 39 so that any free treatment solution carried by the mass of material emptied out of the baskets 16 may be drained away and emptied into the cooking tank 3 or otherwise suitably disposed of. After the material is fed into the washer 5, it is automatically passed therethrough in a continuous flow, and through several washer stages, 40 to a hydrator 44 where the washed pulp is mixed with and diluted by fresh water, a thorough mixing action being assured by a rotating beater wheel 45, disposed transversely of the hydrator 44 which is in the form of a large tank.

50 As indicated in Fig. 1A the last stage of the washer 5 is fed with substantially fresh or clear water which is supplied through a pipe 46 from a source that will be hereafter described, the pipe 46 having a connection 47 with the washer shell or housing.

55 The last stage of the washer 5 is provided with a drain connection 48, at its entering end, which leads to the intake side of a pump, not shown, the discharge side of which leads to the connection 49 at the leaving end of the next preceding washer stage. This next stage of the washer 5 is likewise provided with a drain connection 50 leading to a pump 51 which delivers washings from this stage of the washer to the first stage thereof through a connection 52.

60 At the bottom of the entering end of the first section of the washer 5 is a connection 53 which leads to the settling tank 8 in which the washings containing the lignins and other materials removed from the straw by the washer are collected so that solids and other heavy undisolved materials removed from the straw in the washing operation may settle out.

65 The remaining mixture of dissolved and suspended lignins herein termed the dark liquor

being then removed from the tank 8 to be further treated as will be later described. The washer 5 is shown in detail in Figs. 4 and 5 and comprises in the present embodiment three similar sections arranged in series.

The first section 5.1 comprises a double tubular shell in which are mounted a pair of oppositely rotating screw conveyors 5.2 and 5.3, one having a left-hand helix and the other a right-hand helix, so that while rotating in opposite directions they will each convey material in the same axial direction. The screws 5.2 and 5.3 are disposed in the housing 5.1 so that their helical blades will overlap each other as shown in Fig. 5. Thus as material is fed into the entering end or mouth 5.4, it is engaged by the screws 5.2 and 5.3 and carried by them through the first washer stage to a connection 5.5 which leads to the mouth 5.6 of the second washer stage 5.7.

70 The parallel screws in the housing 5.1 are intermeshed with each other so that as the material is being conveyed axially through the housing it is squeezed between the intermeshed screw blades. The inner walls of the housing 5.1 which are spaced away from the edges of the screw blades 25 are provided with axially extending ribs 5.8 which project inwardly and substantially engage the edges of the helical screw blades. These ribs 5.8 serve to agitate or stir up the material passing through the washers and assist in the 20 squeezing process.

75 The second and third stages 5.7 and 5.9 respectively of the washer are constructed in substantially the same manner as the first stage 5.1 with the exception that the pitch of the conveyor screws may be lessened in order that the squeezing action on the material passing through the washer may be increased.

80 As shown in Fig. 4 the screws of all of the washer stages may be rotated by a single driving means 5.10 which receives its power from a motor, not shown. In such an arrangement the driving means 5.10 may be connected directly to the shafts 5.11 of the third washer stage screws, and the power may be transferred by belts or the like 45 5.12 to the shafts 5.13 of the second washer stage screws. Likewise the shafts 5.14 of the first stage washer screws may be driven by a belt 5.15 from the shafts 5.13.

85 As shown in Fig. 4, fresh water is fed into the washer by means of the conduit 46 and connection 47 which water in passing through the washer in a direction counter to the movement of the material within the same serves as a vehicle as well as a rinsing agent, and in passing backwardly from stage to stage, through the agency of the pipe connections 48, 49, 50 and 52 and the associated pumps, one of which is shown at 51, carries with it the squeezed-out lignins in increasing concentration for final delivery of such 60 lignins through the pipe 53 to the settling tank 8. After passing through the third stage 5.9 of the washer, the material is discharged through the connection 5.16 into the hydrator 44.

90 After being diluted in the hydrator 44 the washed pulp is conveyed through a conduit 54 to a paddle-wheel beater 55 which feeds the material into the refiner 6, wherein the fibres are beaten and separated from each other and finally 70 delivered as completely refined pulp to a conduit 56 having connection with the outlet end 57 of the refiner.

95 The paddle-wheel beater 55 is in the nature of a continuation of the conduit 54 and connection 75

for the same with the entering end of the refiner 6.

The central portion of the beater 55 has horizontally cylindrical side walls between which is mounted a paddle-wheel 58 which is rotated by a motor 59 through a belt 60 and which drags the pulp over a plurality of projections 61 on the inner surface of the beater walls. At the bottom of the beater 55 is a trap 62 provided with a 5 clean-out door 63 for the removal of any heavy 10 solid impurities that may have passed through the hydrator.

The refiner 6 is shown in detail in Fig. 6 of the drawings, and comprises a plurality of cylindrical sections arranged in an end to end series, with each section having a greater diameter than the next preceding section.

The first section 6.1 is a pump and houses an impeller 6.2 which is shown in detail in Fig. 7, which illustrates the same from the entering side. The walls of the section 6.1 are provided with a plurality of axial ribs 6.3 which serve to effect a beating action on the pulp material as it passes through the pump impeller 6.2, and into the second stage 6.4 of the refiner.

The second refiner stage 6.4 houses a single wheel 6.5, the entering side of which is shown in Fig. 8. The wheel 6.5 is made up of two identical sections arranged back to back, each comprising a disk on one face of which are formed a plurality of radially curved blades 6.6.

Thus, when the wheel 6.5 is rotated the leading surface of the blade 6.6 on the entering side will be convex and the leading surface of the blade 6.7 on the leaving side will be concave, whereby a centrifugally outward force will be applied to the material on entering the section 6.4 and a scooping inward force will be applied to the material on the opposite side of the wheel to expel the same from the section 6.4 axially into the next section 6.8, the entering side of the wheel 6.5 acting as a centrifugal impeller and the leaving side acting as a pump to draw the material through the section.

The third stage 6.8 of the refiner as shown is divided into three similar portions, each of which houses a wheel 6.9, the form of which is illustrated in Fig. 9.

The wheels 6.9 are similar to the wheels 6.5 except that the blades are greater in number and are not as wide, and this wheel is likewise made up of two identical sections like that shown in Fig. 9 arranged back to back so that the action of each wheel will be the same as that of the 55 wheel 6.5.

The fourth stage 6.10 of the refiner is substantially the same as section 6.8 except that it is of greater diameter; and the wheels 6.11 housed therein are likewise of the same construction as 60 the wheels 6.9 except that they are of greater diameter, and of lesser width.

The fifth stage 6.12 of the refiner comprises four similar sections, each of which houses a wheel 6.13 which is shown in Fig. 10. The wheel 65 6.13 is provided on each face with a plurality of radial and annular ribs or blades and the periphery of this wheel is provided with a large number of closely spaced radially projecting blades. Both sides of the wheel 6.13 are identical and this 70 wheel may therefore be readily made in one single piece.

The last or final stage 6.14 of the refiner is of the same diameter as the fifth stage 6.12, and comprises a single section housing a pump wheel 75 6.15 which serves to expel the refined pulp into

the outlet 57, the wheel 6.15 being simply a paddle-wheel type impeller as shown in Fig. 11.

Each section of each stage of the refiner is provided with a plurality of annularly spaced 5 ribs 6.16 which extend radially along each section end wall and axially along the side wall whereby the pulp as it passes through the several refiner wheels is thoroughly beaten between the ribs 6.16 and the blades of the wheel to separate the pulp fibres.

The clearance between the edges of the ribs 6.16 and the edges of the blades on the several 10 wheels is of varying amounts, being widest in the first or intake and pumping section and decreasing slightly in each successive section, and in 15 each portion of each section, progressively toward the last or discharge pump section. Thus as the pulp passes through the device it is subjected to a continuous and rapid centrifugal or turbine 20 whirling action between beating sections of progressively increasing fineness with the result that 25 the fibres are completely separated laterally from each other and the pulp substantially fluffed, the fibres being fine but long and possessing greater strength than is had in ordinary processes.

During the refining process it is necessary to mix fresh water with the pulp to further dilute it and aid in the separation of the fibres. Such water is supplied by a connection 64 which is a 30 branch of the conduit 46 shown in Fig. 1A. The connection 64 is brought into a header 6.17 formed on the outside of the fifth stage 6.12 of the refiner, there being a plurality of small openings 6.18 in the side wall of each section of the stage 6.12 communicating with the interior of 35 the header 6.17, whereby fresh water supplied by the connection 64 is distributed substantially uniformly to each section of the final refiner stage in relatively fine streams.

All of the refiner wheels are mounted on and 40 carried by a single shaft 65 which extends axially through the refiner, and which is driven by a motor 66.

From the conduit 56 the refined pulp is delivered into a tank 67 in which a plurality of pulp-collecting cylinders 7 are mounted on horizontal axes. The pulp-collecting cylinders, while not shown in detail, are hollow cylindrical devices the cylindrical surface of which is formed of heavy wire mesh on which the pulp fibres are picked up 45 and transferred to a moving felt blanket 68, each successive couch roll transferring a successive layer of fibre onto the blanket 68 so that a sheet of fibre is built up. This sheet after passing through squeeze rolls 69 is delivered as a continuous sheet of pulp which may be cut or folded 50 and stacked on a truck as shown at 70 in Fig. 1B.

As indicated in Fig. 1B the couch rolls 7 are mounted on hollow trunnions which communicate with the interior of the rolls and a pipe 71 55 is connected between each hollow trunnion and a header 72 which is connected to the intake side of a pump 73, the discharge side of the pump being connected directly with the pipe 46 which 60 supplies fresh water to the refiner and to the 65 washer.

The water withdrawn from the tank 67 by the pipes 71 creates a flow of pulp toward the cylindrical surface of each of the cylinders 7 so that as 70 the water passes through the wire mesh thereof the pulp is deposited on the outside of the mesh to be carried thereby upwardly to the felt blanket 68. Water removed from the tank 67 by the pump 73 and supplied to the refiner and washer 75 is substantially replaced by the water which car-

ries the pulp from the refiner through the conduit 56 to the tank 67. However, additional fresh water is supplied to the tank 67, to make up that passing through the washer 5 and to maintain the water in the tank 67 at a proper level, by means of a fresh water supply line which is not shown.

The washings removed from the washer 5 and stored in the tank 8 comprise the lignins, removed from the straw by the treating and washing processes, dissolved in caustic soda liquor and it is part of the purpose of the herein described invention to recover the caustic soda from the washings for use in making up fresh caustic soda solution for the cooking tank 3, the procedure being part of a continuous cycle of operation whereby make up soda is automatically provided to maintain the supply of treatment liquor at a proper concentration. As shown in Fig. 1A the washings held in the settling tank 8 are removed at the upper part of the tank by a pump 74 having intake connection 75 with the tank 8 and a discharge connection 76 which leads to the soda recovery apparatus 9, the washings or dark liquor first passing through a heating tank 77 in which is mounted a steam coil 78 for the purpose of heating the dark liquor to a temperature suitable for the soda recovery process, the dark liquor being extracted from the tank 77 by a pump 79 and delivered by a conduit 80 to the soda recovery apparatus.

It has been found desirable in many cases to evaporate the dark liquor during the heating process in order to increase the concentration of the lignins in the liquor as it is delivered to the recovery device 9, thus obtaining a lignin by-product containing a lesser amount of water, and it will be understood that the tank 77 may also be constructed to serve as an evaporator as well as a heater.

The soda recovery process is one utilizing the phenomena of dialysis which is a well known method of separating bodies based on their unequal diffusibility characteristics, that is with a mixture of bodies having unequal diffusibility characteristics placed on one side of a porous membrane such as a sheet of parchment paper and placing water on the other side of the membrane, the body having the greatest diffusibility characteristic will pass through the membrane and into the water.

In the soda recovery apparatus 9 the dark solution is passed over one side of a porous membrane and substantially clear water is passed over the other side of the said membrane, the soda, having the greatest diffusibility characteristic, passing through the membrane and into the water in which it is readily utilized as will be hereafter described. The substantially fresh water supply of the soda recovery apparatus is provided by a conduit 81 which is a branch of the conduit 46 as shown in Fig. 1B, the water being supplied by the pump 73 which takes such water from the tank 67.

The soda recovery apparatus of the dializer is shown in detail in Figs. 12 to 16 inclusive. As shown in Fig. 12 the dializer comprises a housing 9.1 in which a plurality of dializer sections 9.2 are supported on a steel frame-work comprising vertical steel members 9.3 and a plurality of horizontal cross bars 9.4.

There are two supporting frames such as shown in Fig. 12, wherein only the nearest frame appears, which are positioned side by side and the dializer sections 9.2 are supported between these

frames on the cross-bars 9.4. Each dializer section is made up of a plurality of plates 9.5 and 9.6, such as shown in Figs. 13 and 14, arranged face to face alternately.

A diaphragm of porous membrane 9.7 such as parchment or the like is disposed between each of the plates comprising the dializer section and these plates, together with the membrane 9.7 are clamped together face to face as shown in Figs. 15 and 16 by a header plate 9.8 which is put under pressure by a screw jack 9.9. The liquids passing through the dializer plates travel in opposite directions relative to each other through passages in the plates as will be hereafter described. As shown in Fig. 12 the dark liquor taken from the tank 77 by the pump 79 enters the dializer at the upper corner of one end and leaves at the diagonally opposite lower corner of the opposite end. It is preferable that the dark liquor from the tank 77 pass through the dializer sections serially and thus flexible connections 9.10 are connected between the dark liquor exit port of one section and the dark liquor entrance port of the next succeeding section, and after leaving the last or final dializer section the dark liquor passes through a conduit 9.11 to a lignin storage tank 82, the dark liquor entering the tank 82 having had substantially all of its soda content removed in the dializer.

As shown in Fig. 12, the conduit 9.11 is connected to the last dializer section by a flexible connection 9.12 in order to permit movement of the header plate 9.8 for the disassembly of the plates comprising the dializer sections.

The substantially fresh water, herein termed the white liquor, is supplied to the dializer sections through the pipe 81 which has connections with the dializer sections on the same side thereof as the dark liquor exit ports, but at the corner vertically opposite the said dark liquor exit ports. Thus the white liquor passes through the dializer in a direction opposite to that taken by the dark liquor and leaves the dializer at the corner vertically opposite the dark liquor entrance port.

As shown in Fig. 12 the white liquor passes through one section only of the several dializers, and the supply pipe 81 is connected with the several dializer sections by means of flexible branch connections 9.13, the white liquor exit connections 9.14 being connected to a header 9.15 which leads to a conduit 83.

In order to keep the liquors from cooling as they pass through the dializer and to maintain the temperature thereof at the point most suitable for maximum dializing action, a heating coil 9.16 is provided in some suitable portion of the housing 9.1 such as at the bottom thereof as shown in Fig. 12.

Referring to Figs. 13 to 16 inclusive, it will be seen that the alternating dializer plates are each provided with a tortuous passageway which travels back and forth across the face of the plate from one corner thereof to a diagonally opposite corner thereof. The passageways of the two plates 9.5 and 9.6 are arranged so as to be substantially in registration when the plates are set face to face. However the passageway of one plate begins and ends at horizontally opposite corners from which the passageway of the alternate plate begins and ends.

Referring in detail to Fig. 13 the passageway 9.17 of the plate 9.5 which shall be considered as a dark liquor plate begins at the upper left-hand corner of the plate as shown in Fig. 13 and travels back and forth across the face of the plate ter-

minating at the lower right-hand corner thereof.

The beginning end of the passageway 9.17 communicates with an aperture 9.18, which extends through the plate from face to face, and the end of the passageway 9.17 is at a similar aperture 9.19 which extends through the plate at the diagonally opposite corner from the aperture 9.18. The passageway 9.17 extends entirely through the plate from face to face, but for purposes of strength bridges of metal 9.20 are formed to span the passageway 9.17 in a manner shown in Fig. 13, the bridges being provided by leaving a portion of the material having about one-half the thickness of the plate at the time the plate is formed, the lesser thickness of the bridge 9.20 permitting the liquor to pass by the same as it travels along the passageway 9.17.

The plate 9.6 shown in Fig. 14 is substantially the same as the plate 9.5, except that the passageway 9.21 begins and ends at horizontally opposite corners of the plate, relative to the passageway of the plate 9.5, the passageway 9.21 beginning at the aperture 9.22, and ending at the aperture 9.23.

As heretofore stated, the passageways 9.17 and 9.21 in the plates 9.5 and 9.6 respectively are arranged so as to be in registry when the plates are mounted face to face on the supporting bars 9.4, and as will be noted from Figs. 15 and 16 the apertures 9.18 and 9.19 of the plate 9.5 will be in registry with apertures 9.24 and 9.25 of the plate 9.6, the latter two apertures having no connection with the passageway 9.21. Likewise the apertures 9.22 and 9.23 of plate 6 will be in registry with apertures 9.26 and 9.27 of plate 9.5 which likewise have no connection with the passageway 9.17. Thus by referring to Figures 15 and 16, it will be seen that the registering apertures 9.18 and 9.24, of the alternate plates, form a continuous intake passageway through the assembled plates comprising the dializer section and likewise the registering apertures 9.19 and 9.25 form a continuous discharge passageway through the section, so that entering dark liquor flowing through the passageway formed by the registered apertures 9.18 and 9.24 will flow through the channels 9.17 of the respective dark liquor plates 9.5 only, the membrane 9.7 serving as a gasket between the adjacent plates 9.5 and 9.6.

Likewise with reference to Fig. 16 entering fresh water flowing through the passageway formed by the registering apertures 9.22 and 9.26 will flow only through the channels 9.21 of the respective white liquor plates 9.6 to the exit passageway through the section formed by the registering apertures 9.23 and 9.27.

The direction of flow of the liquids relative to the assembled plates is indicated by the arrows in Figs. 15 and 16.

As has been heretofore stated, the action of the dializer is that of diffusing a body, carried in one liquor, through a porous membrane into another liquor, and since the passageways 9.17 and 9.21 are in registry a relatively large area of porous membrane is exposed to the two liquids. The white liquid is passed through one dializer section only, in order that a maximum absorption in each section may be had, and the dark liquor is passed through the several dializer sections serially in order to increase the length of its time in contact with the membrane to assure a maximum extraction of the soda from the dark liquor solution.

Upon leaving the soda recovery unit 9, the white liquor containing the extracted soda is carried by

the pipe 83 to a reclaimed soda storage tank 84 indicated in dotted outline in Fig. 1B.

From the storage tank 84 the white liquor is carried by a pipe 85 to a pump 86 and thence to a conduit 87 which branches through a two-way valve 88 to a connection 89 leading into a caustic solution-mixing equipment 90, the connection 89 being in the form of a spray pipe arranged to spray the liquor over a plurality of baskets 91 which are filled with a mixture of lime and soda ash and which are arranged to be turned or spun, in a manner and by a means not shown, in order to thoroughly saturate the solution sprayed by the pipe 89. The caustic solution-mixing equipment 90 is positioned directly over the tank 10 and is separated therefrom by a floor 92 in which are a series of dump valves 93 whereby the recharged liquid from the tank 90 can be released into the tank 10.

A connection between the tank 10 and conduit 85 is had through a three-way valve 94 which is employed in conjunction with the valve 88 to provide for recirculation of the liquid in the tank 10 through the charging equipment 90 or for transferring the charged liquid from the tank 10 to the elevated tank 11. From the tank 11 the solution is slowly released into the series of settling towers 12 in which a precipitate of calcium carbonate is settled out of the liquid, the remaining caustic soda solution passing by means of the conduit 13 to the main storage tanks 14.

The storage tanks 14 are arranged in series and the treatment solution is transferred from them to the cooking tank 3 by means of a pump 95 and the intake and discharge pipes 96 and 97 respectively.

During the performance of the herein-described treatment process considerable soda normally present in the natural straw is removed therefrom during the cooking treatment, some of which is carried into the washer from which it passes into the settling tank 8. The soda which is released and dissolved in the cooking tank solution serves to maintain the proper concentration in the cooking liquor and replace to a certain extent the soda entrained with the straw as it is removed from the cooking tank. The additional soda extracted from the straw that passes to the tank 8 is recovered in the dializer 9.

Normally several cooks or cooking tank loads of raw material are required before a chemical equilibrium in the treatment solution cycle is reached during which soda must be put into the system. However, after these several cooks, it is found that an excess of soda appears which must be removed from the system in order to keep the proper degree of concentration in the treatment solution and such excess soda upon removal from the system becomes a commercial by-product of the system. Thus the system is substantially self-maintaining as far as the soda is concerned, which materially reduces the operating costs as compared with other known straw treatment processes.

With the herein-described pulp making apparatus every component of the raw natural straw that has commercial value is extracted, substantially refined and utilized as a by-product. The by-product production finally reaching a point where its value is greater than that of the pulp that is produced. Thus the entire apparatus may ultimately serve principally for the extraction of chemicals and lignins from straw and the like and the pulp production may become a secondary or by-product factor.

Although but one specific embodiment of this invention has been herein shown and described, it will be understood that details of the disclosure may be modified or omitted without departing from the spirit of this invention as defined in the following claims.

I claim:

1. A pulp refining device comprising a shell having intake and discharge openings, a rotatable shaft extending axially in said shell, a disc-like wheel mounted on said shaft and within said shell, a plurality of radially curved blades on the surface on each side of said disc-like wheel, the blades on one side of said wheel being curved away from the direction of rotation thereof and the blades on the other side being curved toward the said direction of rotation, and a plurality of spaced fins on the inner surface of said shell projecting toward said wheel and extending in a direction transverse to the plane of rotation thereof.
2. A pulp beating wheel comprising a disc having a central hub, and a plurality of radially curved blades projecting from the surface of each side of said disc, said blades extending radially outward from adjacent said hub, and the blades on the two sides of said disc being curved in respectively opposite angular directions.
3. A pulp beating wheel comprising a disc-like member having a central hub, and a plurality of blades on the surface of each side of said disc-like member, said blades being spaced angularly about the axis of said disc member and extending radially beyond the periphery of said member where they are joined to form substantially radial peripheral fins.
4. A pulp beating wheel comprising a disc-like member having a central hub and a serrated periphery, and a plurality of blades projecting from the surface of each side of said disc member, said blades extending radially outward toward the periphery of said disc member and each terminating at the crest of a respective one of said serrations.
5. A pulp beating wheel comprising a disc-like member having a central hub and a serrated periphery, and a plurality of radially curved blades projecting from the surface of each side of said disc member, said blades extending radially outward toward the periphery of said disc member, each terminating at the crest of a respective one of said serrations, and the blades on the two sides of said disc being curved in respectively opposite angular directions.
6. A pulp refining device comprising a plurality of cylindrical stages of progressively increasing diameter arranged in end to end series, each stage being of uniform diameter from end to end and comprising a plurality of cylindrical sections arranged end to end, each section having end walls and an opening in each end wall, a rotatable shaft extending axially through said stages, a plurality of disc-like beating wheels mounted on said shaft one within each of said sections and each having a plurality of radial blades spaced angularly about its axis, and each of said sections having a plurality of fins on its inner surface, said fins projecting toward the respective wheel and extending in a direction transverse to the plane of rotation thereof.
7. A pulp beating wheel comprising a disc-like member having a central hub, and a plurality of blades on the surface of each side of said disc-like member, said blades being spaced angularly about the axis of said disc-like member and extending radially beyond the periphery of said member where they are joined to form substantially radial

peripheral fins, and the blades on the two sides of said disc being curved in respectively opposite angular directions.

8. A pulp refining device comprising a shell defining a pulp beating chamber having a substantially cylindrical outer wall and spaced, substantially parallel, end walls, intake and discharge openings in the end walls, a rotatable shaft extending through the openings, a beater wheel secured on the shaft for rotation within the chamber and having an outer periphery extending radially beyond the openings, a plurality of circumferentially spaced fins on the inner surface of the shell and directed substantially radially toward the wheel, said fins being substantially U-shaped and extending substantially continuously across both end walls and the outer wall of the chamber between the inlet and outlet openings, adjacent fins forming a series of circumferentially arranged U-shaped pockets enveloping peripheral marginal portions of the wheel, and a plurality of ribs on the wheel arranged for cooperative beating action with the fins on the shell upon rotation of the wheel to separate the fibres of material carried through the shell in suspension.

9. A pulp refining device comprising a shell defining a pulp beating chamber having a substantially cylindrical outer wall and spaced, substantially parallel, end walls, intake and discharge openings in the end walls, a rotatable shaft extending through the openings, a beater wheel secured on the shaft for rotation within the chamber and having an outer periphery extending radially beyond the openings, a plurality of circumferentially spaced fins on the inner surface of the shell and directed substantially radially toward the wheel, said fins being substantially U-shaped and extending substantially continuously across both end walls and the outer wall of the chamber between the inlet and outlet openings, adjacent fins forming a series of circumferentially arranged U-shaped pockets enveloping peripheral marginal portions of the wheel, and a plurality of ribs on the wheel arranged for cooperative beating action with the fins on the shell upon rotation of the wheel, said wheel ribs being substantially radially disposed and extending beyond the peripheral margins of the wheel to permit the passage of material between adjacent ribs from one side of the wheel to the other in the beater chamber.

10. A pulp refining device comprising a shell defining a pulp beating chamber having a substantially cylindrical outer wall and spaced, substantially parallel, end walls, intake and discharge openings in the end walls, a rotatable shaft extending through the openings, a beater wheel secured on the shaft for rotation within the chamber and having an outer periphery extending radially beyond the openings, a plurality of circumferentially spaced fins on the inner surface of the shell and directed substantially radially toward the wheel, said fins being substantially U-shaped and extending substantially continuously across both end walls and the outer wall of the chamber between the inlet and outlet openings, adjacent fins forming a series of circumferentially arranged U-shaped pockets enveloping peripheral marginal portions of the wheel, and a plurality of ribs on the wheel arranged for cooperative beating action with the fins on the shell upon rotation of the wheel, said ribs being formed on both sides of the beater wheel, the ribs on one side cooperating with fins on the end wall of the

chamber having the inlet opening and the ribs on the opposite side of the wheel cooperating with the fins on the end wall of the chamber having the outlet opening.

- 5 11. A pulp refining device comprising a shell defining a pulp beating chamber having a substantially cylindrical outer wall and spaced, substantially parallel, end walls, intake and discharge openings in the end walls, a rotatable shaft extending through the openings, a beater wheel secured on the shaft for rotation within the chamber and having an outer periphery extending radially beyond the openings, a plurality of circumferentially spaced fins on the inner surface of 10 the shell and directed substantially radially toward the wheel, said fins being substantially U-shaped and extending substantially continuously across both end walls and the outer wall of the 15

chamber between the inlet and outlet openings, adjacent fins forming a series of circumferentially arranged U-shaped pockets enveloping peripheral marginal portions of the wheel, and a plurality of ribs on both sides of the beater wheel arranged for cooperative beating action with the fins on the shell upon rotation of the wheel to separate the fibres of material carried through the shell in suspension, said ribs substantially radially disposed with respect to the shaft and extending beyond the peripheral margins of the wheel so that suspended material passes between adjacent ribs in moving through the U-shaped pockets of the chamber around the wheel periphery from the inlet opening side thereof to the outlet opening side thereof.

MAX SKOLNIK.
